UNDERWATER TELEVISION CAMERA HOUSING OR SIMILAR ARTICLE

Herbert F. Sampson, Costa Mesa, Calif.

Application April 6, 1959, Serial No. 55,354

Term of patent 14 years

(Cl. D61—1)

Fig. 1 is a perspective view of an underwater television camera housing showing my new design.

Fig. 2 is a side view thereof.

Fig. 3 is a front view thereof.

Fig. 4 is a bottom view thereof.

Fig. 5 is a rear view thereof.

Fig. 6 is a perspective view of the camera shown in Fig. 1 with the rear housing portion rotated 90°.

I claim:

The ornamental design for an underwater television camera housing or similar article, as shown.
